UNITED STATES PATENT OFFICE.

FRANK W. STOCKTON, OF CHICAGO, ILLINOIS.

METHOD FOR PRESERVING TENNIS-BALLS OR OTHER OBJECTS CONTAINING FLUID UNDER PRESSURE.

1,207,813.

Specification of Letters Patent. Patented Dec. 12, 1916.

Original application filed March 6, 1915, Serial No. 12,653. Divided and this application filed August 14, 1915. Serial No. 45,581.

To all whom it may concern:

Be it known that I, FRANK W. STOCKTON, a citizen of the United States, and a resident of the city of Chicago, county of Cook, and State of Illinois, have invented a certain new and useful Method for Preserving Tennis-Balls or other Objects Containing Fluid Under Pressure, of which the following is a specification.

10 This invention relates to a new and useful method of preserving a state of fluid pressure in tennis balls or other objects containing fluid under pressure, the present application being a division of my pending 15 application, Serial No. 12,653, filed March 6, 1915, for method and apparatus for preserving tennis balls or other balls.

The object of my invention is the production of a method of the character and for 20 the purpose mentioned whereby the pressure in a tennis ball or other object may be preserved notwithstanding that the object may be unused or stored away for a great length of time.

25 A further object is the production of a method as mentioned through the medium of which the internal pressure in a tennis ball or other object may be preserved at a low cost.

30 Other objects will appear hereinafter.

With these objects in view, the invention consists in the method hereinafter described and claimed.

The invention will be best understood by 35 reference to the accompanying drawing forming a part of this specification and in which the figure is a central section through a receptacle containing a ball, said receptacle being designed especially for use 40 in the process forming the subject matter of this application.

In the employment of this method for the preservation of a tennis ball or other object containing fluid under pressure, a receptacle 1 in the form of an ordinary sheet metal can is employed which is of a size adapting the same to accommodate the object 2 whose pressure it is desired to preserve. The receptacle 1 is open at its upper 45 end and is provided with a cover 3 which is adapted to be hermetically sealed in operative position after the object 2 has been placed in the receptacle.

The preserving method forming the sub-

ject matter of this application contemplates 55 the creation of a fluid pressure in the receptacle 1 around the ball or object 2 after the cover 3 has been sealed in position, the creation of this pressure being brought about through chemical reaction. In this connection, in order to secure the desired chemical reaction, the receptacle will be provided with a calculated amount of a suitable chemical such as ammonium-nitrite placed in the bottom of the receptacle, the latter 65 being provided with one or more cups 4 to accommodate the chemical. This having been done, upon the receptacle being hermetically sealed, through sealing of the cover 3 in position, the receptacle is suitably 70 heated. When this is done, the ammonium-nitrite will be decomposed and generate a large volume of gas. The gas thus generated will produce the fluid pressure desired within the receptacle provided the calculated amount of ammonium-nitrite has been used.

It will be seen that with the pressure in the receptacle surrounding the ball or object 2 the same as that of the interior of the 80 latter, the possibility of leakage from the ball or object is prevented and thus reduction of pressure of the same prevented. The possibility of leakage from the ball or object being precluded, the same may be 85 kept indefinitely without deterioration through softening, such as results at the present time where a ball, such as a tennis ball is kept from one season to another or for a considerable period of time. 90

While I have mentioned but one chemical in connection with the creation of fluid pressure within the receptacle, it is understood that I do not limit myself specifically to its use, inasmuch as it is possible that other 95 chemicals may as easily and readily be used. I, therefore, wish it understood that I desire to avail myself of the use of any other chemicals which come within the scope of my invention as defined by the appended claims. 100

Having described my invention what I claim as new and desire to secure by Letters Patent is:

1. The method of preserving a state of 105 fluid pressure in an object during storage and prior to use of the object, which consists in inclosing the object in a hermetically

sealed container, and then creating a fluid pressure in the container around the object.

2. The method of preserving a state of fluid pressure in an object during storage 5 and prior to use of the object, which consists in inclosing the object in a hermetically sealed container, and then creating a fluid pressure in the container around the object substantially the same as that of the pres-
10 sure in the object.

3. The method of preserving a state of fluid pressure in an object which consists in inclosing the object in a hermetically sealed receptacle, and then through chemical re-
15 action creating a fluid pressure in the receptacle around the object.

4. The method of preserving a state of fluid pressure in an object during storage and prior to use of the object, which con-
20 sists in inclosing the object in a hermetically

sealed container, and then through chemi-
cal reaction, within the container, creating a fluid pressure in the container around the object.

5. The method of preserving a state of fluid pressure in an object during storage and prior to use of the object, which consists in inclosing the object in a hermetically sealed container, and then, through chemi-
25 cal reaction, within the container, creating 30 a fluid pressure in the container around the object substantially the same as that of the pressure in the object.

In testimony whereof I have signed my name to this specification in the presence of 35 two subscribing witnesses.

FRANK W. STOCKTON.
